Primary Examiner — Amy C Wierenga*Assistant Examiner* — Kathryn Elizabeth Zieno(74) *Attorney, Agent, or Firm* — Larson & Larson; Justin P. Miller; Frank Liebenow(57) **CLAIM**

I claim The ornamental design for a leaf screen connector, as shown and described.

DESCRIPTION

FIG. 1 is a top perspective view of a leaf screen connector showing my new design;

FIG. 2 is a bottom perspective view thereof;

FIG. 3 is a top plan view thereof;

FIG. 4 is a bottom plan view thereof;

FIG. 5 is a right-side elevation view thereof;

FIG. 6 is a left-side elevation view thereof;

FIG. 7 is a front elevation view thereof;

FIG. 8 is a back elevation view thereof; and,

FIG. 9 is a perspective view showing the leaf screen connector in a position of use in its environment.

The broken-away symbols in the drawings indicate the appearance of any portion of the article between the break lines forms no part of the claimed design.

The broken lines shown in FIG. 9 illustrate environmental leaf screens and form no part of the claimed design.
